PARAFFIN SCRAPER

James A. Smethers, Odessa, Tex.

Application August 24, 1940, Serial No. 354,053

7 Claims. (Cl. 166—18)

This invention relates to a tool for cleaning oil wells. More particularly it relates to a tool for scraping material, such as paraffin, from the tubing or casing in an oil well.

As is well understood, in the production of paraffin base oils, a portion of the paraffin is deposited on the walls of the casing or tubing through which the oil is produced, thus gradually reducing the effective cross section of the tubing through which the oil must pass, and possibly eventually blocking the tubing entirely. This results in a reduction of the output of the well, or even a complete cessation thereof.

It is an important object of the present invention to provide an improved tool for removing such accumulation of paraffin from the well tubing.

It is another object of this invention to provide a tool for this purpose which acts to break the paraffin into small pieces, so that it will pass more readily from the tubing.

It is still another object of this invention to provide such a tool having a plurality of cutters, the cutters being capable of acting independently of each other.

It is a still further object of this invention to provide such a tool capable of striking a blow on the cutters, or acting as a jar, to loosen the cutters or the paraffin into which they may have been forced.

This invention possesses many other advantages, and has other objects which may be made more easily apparent from a consideration of one embodiment of the invention. For this purpose there is shown a form in the drawing accompanying and forming part of the present specification. This form will now be described in detail, illustrating the general principles of the invention; but it is to be understood that this detailed description is not to be taken in a limiting sense, since the scope of this invention is best defined by the appended claims.

In the drawing:

Figure 1 is an elevation of a tool embodying the invention;

Fig. 2 is an elevation showing the tool as being lowered into the well tubing;

Fig. 3 is a detail of one of the cutters on an enlarged scale; and

Fig. 4 is a cross section of Fig. 3.

Referring to the drawing, Figs. 1 and 3 illustrate the parts of the tool in the relative positions which they occupy when the tool is suspended or running in tubing where no paraffin or the like is encountered, or when being pulled from the

tubing. The tool includes a plurality of cutters, or spinners, 5, 6, 7 and 8, mounted on a long stem or mandrel 9, which is provided with a threaded pin 10 at its upper end, by means of which the tool is attached to a cable 11 or other suitable means known to the art for raising and lowering the tool in the well. This means may include a "sinker bar" to ensure the downward passage of the tool in the well.

Mandrel 9 is shown as having a conventional square portion 12 to accommodate a wrench adjacent pin 10 to assist in removing or attaching the tool from or to the cable. Below the wrench square 12 an annular shoulder 14 is formed. Axially spaced along mandrel 9 is a plurality of stop collars 15, the lower end of each of which forms an annular shoulder 16, the upper end of each being provided with ratchet teeth, as 17, 18. The lower end of the mandrel is provided with a similar collar 19 which however has a substantially flat lower face, and an upper annular shoulder with ratchet teeth 20, similar to those on collars 15.

Cutters 5, 6, 7 are similar, differing only in their outside diameters, hence only one of them, for example cutter 6, will be described. Referring to Fig. 3, it will be noted that the cutter includes a central tubular portion, or long hub 21 which is freely slideable as well as rotatable on mandrel 9. The upper end of hub 21 has an annular surface 22 adapted to engage the shoulder 16 on the collar 15 immediately above the cutter. The lower end of hub 21 has teeth 23 arranged for cooperation with the ratchet teeth, as 18, of the collar immediately below the cutter. Each cutter has a plurality of wings or vanes 25, for example three, as shown, which are in a helix-like or spiral, formation.

The lower cutter 8 differs from the cutter described and shown in Fig. 3 in that its hub 26 is somewhat shorter and the wings or vanes 27 extend beyond the lower end of hub 26 and are joined together forming a point 28. The lower end of hub 26 has ratchet teeth 29 for cooperation with the teeth 20 on collar 19. Collar 19 is accommodated in a space 30 provided within blades 27 below hub 26.

The wings of adjacent cutters have helices of opposite hands; thus the helix of the wings of cutters 5 and 7 are left handed, while the helix of the wings 25 of cutter 6, which is between cutters 5 and 7 is right handed. Similarly the helix of wings 27 of cutter 8 is right handed. Further, as clearly shown in Fig. 1, the outside diameter of the cutters 5, 6, 7 and 8 decreases progressively

toward the lower end of the tool. Thus, cutter 5, at the top of the tool, has an outside diameter over the wings which approximates the inside diameter of the tubing 31 in which the tool is to operate, a working clearance being provided, while cutter 8 is the smallest.

In this way the work to be done and the stress is more or less evenly distributed among the several cutters.

As previously mentioned, the paraffin collects on the wall of the tubing through which the oil is produced. Such a condition is illustrated in Fig. 12, wherein a layer of paraffin is indicated by 32 on the inside of tubing 31.

As the tool is lowered into the well tubing 31, the cutters 5, 6, 7 and 8 are in their lower positions, that is supported on their respective collars with the ratchet teeth engaged, as shown in Fig. 1. When the cutters encounter the paraffin layer 32, their downward movement is retarded, the mandrel 9 however continuing to move downwardly. When the shoulders 16 of the stop collars 15 engage the surfaces 22 of the cutters, the continued downward movement of the mandrel forces the cutters downwardly through the paraffin, and since the cutters are free to rotate on mandrel 9 the wings 25 of the cutters form spiral cuts in the paraffin. Since the spiral cuts formed by adjacent cutters are of opposite hand, the paraffin is very effectively cut into small pieces.

When the mandrel 9 is moved upwardly, the cutters moved outwardly with respect thereto into their original positions of Fig. 1 with their ratchet teeth engaging those of the respective stop collars. This prevents rotation of the cutters on the upward stroke and causes the cutter wings 25 to scrape the paraffin from the tubing. Since the paraffin was cut or broken on the downward stroke of the tool, it is removed from the wall in small pieces which are readily removed from the well.

The forces tending to rotate the tool by the cutters on the up stroke are practically balanced, since the wings on adjacent cutters have spirals in opposite directions. Further, the inertia of the cable or other means supporting the tool, also opposes such rotation.

It may sometimes happen that the paraffin extends entirely across the bore of tube 31. In this case the point 28 of the lower cutter will readily pierce it, enabling the tool to be lowered without difficulty.

It is intended that the scraper be "spudded" or worked up and down in short strokes in a portion of the well until the paraffin is scraped from the wall of that portion. The tool is then lowered and the operation repeated in the next lower portion. With the cutters embedded in the paraffin, as shown in Fig. 2, it is possible to strike a blow on the bottoms of the cutters by rapidly moving the mandrel up. Such a jarring blow assists in breaking up the paraffin and is useful in loosening the cutters if they happen to stick. By this method the well or tubing is cleaned for its entire length without the need of removing the tool until the cleaning is completed.

What is claimed is:

1. In a cleaner adapted for use in a well, a mandrel, a plurality of axially spaced cutters on the mandrel, said cutters being slidable as well as rotatable on the mandrel, stop collars secured to the mandrel between adjacent cutters to limit the axial movement of the cutters on the mandrel, each of said collars having means on one face thereof adapted to prevent rotation of a

cutter when said cutter engages the face, each of said cutters including wings adapted to impart rotation to the cutter as the cutter is moved axially through the well, said wings being so arranged that the rotation imparted to adjacent cutters is in opposite directions.

2. In a cleaner adapted for use in a well, a mandrel, a plurality of axially spaced cutters on the mandrel, said cutters being slidable as well as rotatable on the mandrel, means to limit the axial movement of the cutters on the mandrel as well as to prevent rotation of the cutters in one direction, each of said cutters having wings adapted to cause rotation of the cutter as the cleaner is moved through the well, the outside diameter of the top cutter being substantially the same as the inside diameter of the well tubing to be cleaned, the outside diameter of the succeeding cutters being progressively less than that of the top cutter.

3. In a well cleaner, a stem arranged for axial movement in the well, a plurality of cutters mounted on the stem in axially spaced relationship, said cutters being arranged for limited axial movement on the stem, the cutters also being rotatable on the stem, means whereby the cutters are held against rotation at one end of their axial movement, each of said cutters having a plurality of helix-like wings, the helices of the wings on adjacent cutters being of opposite hands.

4. In a well cleaner, a mandrel arranged for longitudinal movement in a well, axially spaced cutters on the mandrel, adjacent cutters being separated by a space approximating the length of a cutter, said cutters being slidable axially as well as rotatable on the mandrel, means to restrict the axial movement as well as to restrain the rotary movement of the cutters with respect to the mandrel, each of said cutters having spiral wings adapted to rotate the cutter upon axial movement of the cutter in the well, the wings on said cutters being so arranged as to cause adjacent cutters to rotate in opposite directions in response to said axial movement, the means to restrict the rotary movement acting at one extremity of the axial movement of the cutter with respect to the mandrel to oppose the rotative force of the wings.

5. In a well cleaner, a mandrel, cutters rotatably supported on the mandrel for axial movement therealong, means to limit the axial movements of the cutters with respect to the mandrel to substantially equal amounts, wings on each of said cutters adapted to rotate adjacent cutters in opposite directions in response to axial movement of the cutters in the well, and means to restrict relative rotation between the cutters and the mandrel at one extremity of the axial movement of the cutters with respect to the mandrel.

6. In a well cleaner, a mandrel arranged for longitudinal movement in a well, axially spaced cutters on the mandrel, said cutters being axially slidable as well as rotatable on the mandrel, and having progressively smaller outside diameters toward the lower end of the mandrel, means carried by the cutters adapted to rotate adjacent cutters in opposite directions upon axial movement of the cutters in the well, means carried by the mandrel between adjacent cutters to limit axial movement of the cutters, said means including ratchet teeth for cooperation with one of said adjacent cutters to restrict rotation of said one cutter to one direction.

7. In a well cleaner, a mandrel arranged for

2,295,058

longitudinal movement in a well, axially spaced rotatable cutters on the mandrel, said cutters also being axially slidabale on the mandrel and having successively smaller outside diameters toward the lower end of the mandrel, the lowermost cutter terminating in a point and having a

hub at its upper end, there being a space in said cutter between said hub and the point, said mandrel extending through said hub and having a collar in said space for engaging the lower surface of said hub and supporting the cutter.
